UNITED STATES PATENT OFFICE.

JOHN E. GARDNER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed September 22, 1920. Serial No. 412,077.

Generally my invention relates to a telephone system in which connections are established by subscribers without the intervention of an operator, by the use of automatic 5 switches.

More specifically my invention relates to a system comprising a plurality of main exchanges having branch offices subsidiary to them, wherein after a connection has been established from a calling subscriber in a main exchange to a called subscriber in a branch exchange the said called subscriber may, by operating his calling device pass or transfer the call to a second subscriber, such passing 10 or transferring of a call from one subscriber to another continuing as long as necessary. While hitherto systems have been invented wherein the result stated has been accomplished, all of these were expensive, hard to 15 maintain and more or less unsatisfactory. 20 Herein I have provided an improved and highly efficient system which operates in a novel and very satisfactory manner.

One of the important features of my 25 invention is the provision of means whereby the called party may transfer the call to another subscriber in the same exchange by using a simple and efficient finder switch, interlinked with the incoming selector in a 30 large system, and the incoming connector in a system of limited capacity, such as 100 lines. By the provision of these finder switches, the incoming selectors or connectors, as the case may be, are rendered operable 35 under control of called subscribers to pass or transfer calls to other called subscribers as many times as is necessary, or desirable; the desired result is thus accomplished in an efficient and practical manner. 40 This system can be enlarged to any desired size simply by inserting selectors of any standard type between the selector, interlinked with my improved finder switch, and the connector, thus making a passing call 45 scheme quite practical in a large or small exchange varying from 100 to 1000 subscribers or more. I have also provided means whereby if only an ordinary call is made and no passing is attempted the finder switch and other additional apparatus will 50 remain inoperative. These and other objects and features of my invention will appear fully hereinafter.

Referring now to the drawings:

In Fig. 1, I have shown a trunk line 1 55 and 2, terminating in a selector switch E, of the well known Keith Erickson two wire type, which has been modified according to the features of my invention. At G is shown my improved finder switch interlinked with 60 the selector E. This finder is adapted to hunt for a line in a group of 100 and to this end is provided with a vertical bank of ten contacts, one for each level, and a second private bank adapted to be engaged 65 by a rotary test wiper. The selector switch E is also provided with vertical and rotary test banks, in addition to the regular line and private banks.

The line and private banks are multiplied 70 locally into the finder switch interlinked with the selector E as are the vertical and rotary test banks. The vertical banks of both selectors and finder are adapted to be engaged by two vertical wipers so constructed that each will be controlled directly by the operation of its corresponding switch shaft vertically, but will not be affected by its rotation. The vertical wiper may be attached to the cup spring case of any Strowger switch, as shown in Fig. 3. At 138, 139 and 140 I have shown a multiple of the trunk line comprising conductors 1 and 2 which goes to multiple bank contacts in the local branch exchange first selectors and which is 85 used for outgoing calls from the local exchange over the trunk line 1 and 2.

In Fig. 2, I have shown a connector switch of a standard two wire type modified to adapt it to operate in my improved system 90 and which is accessible in common with a number of other similar connector switches to selectors, one of which is shown at E.

The system shown in Figs. 1 and 2 is adapted to operate in a 1000 line branch exchange, but can be readily enlarged to any capacity by inserting selector switches between the selector E and connector H as indicated before.

Fig. 4, shows a modification of my improved system which is adapted to operate in a small branch exchange of not over 100 lines and consists of a finder switch N similar to that shown at G, interlinked with a connector L, which is very similar to that 105 shown at H. The same number of banks,

multipled in the same manner, as those of the selector E and finder G, are used in this system as shown in Fig. 4.

While in the drawings I have shown a plurality of batteries it will be understood that there is preferably but one battery for each exchange having its positive pole grounded.

I will now describe the operation of my system when a subscriber at the main exchange calls a subscriber in the branch exchange.

The operation of the switches in the main exchange is well known, being shown in Fig. 15 of United States Letters Patent to Talbot G. Martin 1,136,912 granted April 20, 1915, and hence it will be unnecessary to describe their operation except in a very general way.

Upon the calling subscriber in the main exchange seizing the trunk line 1, 2 by means of a selector repeater (not shown) in the main exchange, a circuit is closed at the repeater for the line relay 6 over the conductors 1 and 2 in series. Relay 6 attracts its armature and closes the circuit of the slow release relay 7, which operates to prepare the vertical magnet circuit at springs 13 and 14 in the well known manner, and also places ground on the release trunk 139 extending to the banks of the local first selectors to prevent the trunk line 1, 2 being seized for an outgoing call. When the calling subscriber dials the next digit of the desired number the line relay 6 operates in response thereto in the usual manner and at each retraction of its armature 15 completes a circuit for the vertical magnet 16 in series with slow acting relay 8. The vertical magnet 16 operates to step the shaft carrying the wipers 31 to 35 inclusive to the desired level of bank contacts in which terminate the trunk line conductors 36, 37, and 38 leading to the connector H (Fig. 2). The wiper 34 is the vertical wiper hereinbefore described and is adapted to engage vertical contacts such as 46, and other similar contacts. Upon the first vertical step of the shaft off normal springs 22, 26 and 28 are closed and a circuit is completed from ground G¹, upper armature and make contact of relay 7, conductor 19, armature 20 and its make contact, conductor 21, off normal springs 22, relay 9 to battery. Relay 9 attracts its armature and locks itself over a circuit from ground G², make contact and armature 23 of relay 9, break springs 24 of rotary magnet 17, thence over the previously traced circuit, relay 9 to battery. An instant after the impulses to the vertical magnet have ceased relay 8 retracts its armature and thereby completes a circuit from ground G¹ armature and make contact of relay 7, conductor 19, armature 20 and its break contact, armature 25 and its make contact, rotary magnet 17 to battery. The rotary mag-

net 17 operates to rotate the wipers 31, 32, 33 and 35 onto the first set of bank contacts in the selected level, and to open the locking circuit of relay 9, which deenergizes. The further operation of this selector depends on whether or not the first trunk is busy or idle. If it is busy a ground will be present on the bank contact engaged by wiper 32, whereupon a circuit will be completed from the said ground by way of wiper 32, conductor 29, armature 30 of relay 5 and its break contact conductor 39, armature 24, off normal springs 22 relay 9 to battery; relay 9 operates to again complete the rotary magnet circuit. This alternate operation of rotary magnet 17 and relay 9 will continue until an idle trunk is found which is designated by the numerals 36, 37 and 38. When this occurs there being no ground present on the bank contact engaged by wiper 32, relay 5 is no longer shorted out as was hitherto to the case and will energize in series with relay 9 in the usual manner, relay 9 remaining inoperative on account the relative resistances of the two relays. Relay 5, however, attracts its armatures and extends the trunk conductors 1 and 2 to the line relay 95 of the connector H (Fig. 2). It will be seen that relays 11 and 12 are included in series with the energizing circuit of relay 95. Relay 12 will energize but relay 11 is a polarized differential relay and its local circuit, extending from ground G¹, conductor 19, armature 40, conductor 41, resistance 42, lower winding of relay 11 to battery is completed at the same time as the circuit for its upper winding; therefore this relay will remain inoperative during dial impulses and until battery is reversed over the trunk conductors 36 and 38. Relay 12 however will operate in response to any impulses sent to the line relay 95 of connector H, but its operation will have no effect at this time. It will be seen that condensers 43 and 44 are shunted across each of the relays 11 and 12 and thus the transmission of voice currents will be unaffected by the inclusion of these low resistance relays in the line circuit.

Returning now to the operation of the connector H, when the next digit of the called number is dialled the line relay 95 operates in the usual manner and at each retraction of its armature completes the vertical magnet circuit from ground, break springs of relay 95, armature 55 and its make contact, off normal springs 56, relay 53, vertical magnet 57 to battery. Upon the first vertical step of the shaft, springs 58 close and the vertical magnet circuit is completed by way of these springs, armature 59 of relay 53, which is operated, then through the said relay, vertical magnet 57 to battery. The vertical magnet 57 of connector switch H operates to step the shaft carrying the wipers 75, 76 and 77, opposite the level in

which the desired branch exchange subscriber's line is located. When the last digit of the number is sent a circuit is completed at each retraction of armature 60, from ground 5 G^4 to the rotary magnet 63 in multiple with relay 62, in a well known manner. The rotary magnet 63 steps the wipers 75, 76 and 77 into engagement with the desired line. The energization of relay 62 connects the test 10 wiper 76 with the test relay 61. Now if the line is busy ground will be present on the test contact engaged by the wiper 76, whereupon a circuit will be completed for test relay 61 which will energize, lock itself over a circuit 15 from ground G^5 , armature 66, conductor 67, armature 65 and its make contact, break springs 68, break springs 69, thence through relay 61 to battery; and at springs 70 connect the busy tone to the calling subscriber's line. 20 Upon hearing this tone the calling subscriber will hang up, whereupon line relay 95 of the connector H will deenergize opening the circuit of slow acting release relay 52, which will deenergize, remove ground from conductor 37, and complete the circuit to the release magnet 107. Ground being removed from conductor 37, relay 5 of selector E will deenergize and complete the release magnet circuit of the selector. Thus all switches 25 will be restored to normal.

If the line called, however, were idle no ground would be connected to the private wiper 76 and relay 61 would not energize. Relay 62 would deenergize an instant later 30 and then a circuit may be traced from ground on conductor 67, armature 65 its break contact, lower winding of relay 64, armature 70' and its break contact, wiper 76, bank contact 78, conductor 81, relay 82 of the line switch C, and motor magnet 83 to battery. Relay 82 operates only partially, that is, enough to open its armature break contacts but not to close any of its make contacts due to a mechanical interlocking device 35 controlled by the line relay 82'. Relay 64 operates and locks itself at armature 85, and also closes the ringing circuit for the called subscriber's telephone, which may be traced from generator M, break contact and armature 88 to springs 86, thence over the subscriber's line, his condenser and ringer, springs 87, break spring and armature 89, upper winding of relay 54 to battery. Relay 54 is so adjusted that it will not respond 40 to alternating current. The ringing of the called subscriber A will continue intermittently until he removes his receiver from the switch hook, when relay 54 will energize, lock itself at armature 91, open the ringing circuit at armatures 88 and 89, and connect the subscriber's line to the back bridge relay 90 at these armatures and their make contacts. Relay 90 energizes and at armature 92 and its front contact completes the circuit of slow acting relay 93, which operates 45

to reverse the polarity of the trunk conductors 36 and 38. This reversal of polarity serves to operate a meter on the calling subscriber's line or give supervision to an operator, and also to operate polarized relay 11, 70 since current is now flowing in the same direction in both windings. Relay 11, on attracting its armature 50, connects ground G^8 to the test wipers 33 and 34, bank contacts 45 and 46 and thence to multiple contacts 173 75 and 182 in the banks of interlinked finder G.

Conversation may now take place between the two parties over the heavy conductors, battery being supplied to the calling party from relay 95 and to the called party from 80 relay 90.

Upon the termination of the conversation the release will take place as before described.

Suppose, however, that when the called party answers it is found that the calling subscriber wished some other party in the branch exchange. Under these circumstances the called subscriber will dial the digit 1, relay 90 will retract its armature in 85 response thereto, and an impulse is sent from ground G^6 armature 92 and its back contact, springs 96, relay 97 to battery. Relay 97 attracts its armature, cutting off line relay 95 from the trunk conductors 36 and 38 at springs 102 and 99, locks itself to ground on conductor 150, and prepares a dialing circuit at springs 101. The line relay 95 will not deenergize, however, as a local circuit has been completed for its upper winding from ground G^7 , and armature 102 and its make contact. Upon battery being cut off from the trunk conductors 36 and 38 relay 12 of the selector switch will 100 retract its armature, but relay 11 will remain energized, its local circuit being still completed. Now upon relay 12 retracting its armature a circuit is completed from ground G^8 , armature 50 and its make contact, armature 120 and its break contact, relay 10 to battery; relay 10 attracts its armature, locks itself to ground at G^9 , springs 28, armature 121 and its make contact. 105

Relay 12 in retracting its armature also 110 connects ground G^{22} to conductor 143 and thence to relay 3 at armature 142 and its break contact. Relay 3 will attract its armature and maintain the polarity reversed over the trunk conductors 1 and 2 during the succeeding operations battery being supplied from the windings of relay 4 to the calling subscriber. 115

At armature 122 and its make contact ground is supplied over conductor 123 to 120 the vertical magnet 150 of the finder switch G. The vertical magnet interrupts its own circuit and operates to step the shaft of the finder carrying wipers 160 to 164 inclusive, until the vertical wiper 163 engages the con- 125

tact 173, which has been grounded previously by the operation of polarized relay 11, whereupon a circuit is completed for the vertical test relay 151. Relay 151 operates to transfer the ground on conductor 123 to the rotary magnet and locks itself to ground G^{12} over a circuit through springs 154, conductor 152, armature 153 to battery.

As soon as the shaft of the finder switch stepped off normal the springs 154, 155 and 156 were closed and a circuit is completed from ground G^{12} , springs 155, conductor 157, relay 3 to battery. This circuit is in addition to the one hitherto traced and serves to maintain relay 3 energized during the subsequent operations. This relay is provided so that the calling subscriber will only be charged with his original call during the transferring operation. The rotary magnet 158 will operate to rotate the wipers 160-164 inclusive breaking its own circuit at each rotary step until the rotary test wiper 162 engages contact 182, which has also been grounded by the operation of polarized relay 11, thereupon a circuit will be completed for the rotary test relay 159 which on attracting its armature opens the rotary magnet circuit to stop the further rotation of the switch and locks itself to ground on conductor 152 through make springs 170. Relay 159 also completes a circuit from ground on conductor 152, spring 171, conductor 172, springs 127, off normal springs 26, release magnet 18 of selector E to battery. This release magnet will operate to restore the switch to normal, whereupon relays 5, 10, 11 and 12 will deenergize and the selector E will assume its original position with line relay 6 energized. Relay 10, upon deenergizing, completes a circuit at springs 144 from ground G^{12} , springs 154, conductor 187, springs 144, conductor 188, relay 185 to battery. Relay 185 energizes and locks itself to ground on conductor 152.

It will now be seen that the wipers 160 and 164 are connected to the multiples of the trunk line comprising conductors 36-38 and a circuit may now be traced for line relay 6 of selector E from battery through the upper winding of the said relay break springs 131, junction point 129, conductor 174, wiper 160, bank contact 181, conductor 36, springs 104, conductor 103, springs 101, which were closed by the operation of relay 97, conductor 102, conductor 38, bank contact 180, wiper 164, conductor 175, junction point 128, springs 130, lower winding of relay 6, to ground through the secondary of the induction coil. The primary of the induction coil is connected to a generator. Therefore a tone will be impressed on the trunk conductors 36 and 38 through the medium of the finder switch wipers. This will be audible to the called subscriber who will know that the apparatus is now in a condi-

tion to establish a connection. Upon the first digit of the desired subscriber's number being dialed by subscriber A, relay 90 operates in response to the impulses and repeats them by means of springs 104 to the line relay 6 in the same manner as a repeater. It will now be clear that the called subscriber A will only operate his calling device for the digits of the local subscriber's number, that is, the number he will call to connect with a second party in the local exchange will be the same as the local subscriber's number except that of course the digit 1 is prefixed as has been hereinbefore described to initiate the operation of the finder switch. Upon the first digit of the subscriber's number being called the back bridge relay 90 will retract its armature a plurality of times in response thereto and at springs 104 open the circuit of line relay 6, the selector stepping to the desired level in response to these repeated impulses and automatically rotating to find an idle trunk in the usual manner. By these operations the connection is extended to a connector switch similar to the connector H and a circuit is now completed for the line relay of this connector switch through the springs of the back bridge relay of connector H in the same manner as in the case of the line relay of selector E. The line relay of the connector may now be controlled by the subscriber A to control the operation of this connector switch in completing a connection to another subscriber's line. The operation of this connector switch will be identical with the operation of the connector H which has been already described.

While the calling subscriber's line has been opened by the operation of relay 3 it is still connected inductively with that of the first called party through the condensers 134 and 145 over the heavy line conductors of the finder switch. Therefore, should the line of the second called party be busy the busy tone will be transmitted to both the calling and original called parties in multiple. This being the case, the called party may speak to the calling party and ask him if he desires to be connected with another subscriber. Supposing this to be the case the called party A will replace his receiver on the switchhook whereupon the back bridge relay 90 will deenergize opening at springs 104 the circuit for the line relay of the connector, which will deenergize, and the release of that connector and the selector E will take place in the usual manner. The connector H will not be released however as the conductor 37 has been grounded over a circuit which extends from G^{12} by means of wiper 161 of the finder. In the connector H is a relay 105 which is connected to the release trunk 37. This relay is, therefore energized as long as ground is present on the conductor 37 and

keeps the circuit of the release magnet 107 open at springs 106. The connector H will not be released then as long as the finder switch G remains off normal. Should the 5 calling party at any time during this interval replace his receiver on the switchhook relay 4 will deenergize whereupon a circuit will be completed from ground G¹³, break contact and armature 135, armature 136 and 10 its make contact, springs 137 conductor 138; springs 156, release magnet 184, to battery, this will restore the finder to normal consequently removing ground from the release 15 trunk conductor 37 whereupon the connector H will release.

However, if the calling subscriber holds the line, upon the called party A removing his receiver and dialing another number he 20 will operate the selector E and another connector in the same manner as previously described to establish a connection with a third party. If this party does not respond, called subscriber A can consult with the calling man to determine if another party will suffice; if so, the called party A may release 25 and call again in the same manner as heretofore described.

However, should the second called subscriber answer the back bridge relay of the 30 connector will energize and close the circuit for the reversing relay in the same manner as described in the operation of connector H. Upon the polarity being reversed relay 11 in the selector E will operate placing ground G⁸ on the conductor 139, springs 186 which are now closed, springs 156, release magnet 184 of the finder switch to battery. This will release the finder G and the connector H will be released upon the original 40 called subscriber A replacing his receiver. Ground G⁸ is also placed on the vertical and rotary test wipers 33 and 34 respectively, to enable the finder G to find the multiple of the trunk line going to the connector 45 which has been operated to connect with the third called party if it should be necessary to pass the call to a fourth party.

Upon the release of the finder G ground is removed from conductor 157 consequently 50 relay 3 will deenergize and conversation may take place over the same circuit through the selector E as originally used.

All the apparatus used in the passing of the call is now normal and the third called 55 party may, in identically the same manner pass the call to a fourth party and so on, as long as desirable.

Upon the termination of the conversation the calling and called parties will replace 60 their receivers on the switchhook, whereupon all the switches will be restored to normal in the usual manner, as has hitherto been described in the setting up of an ordinary connection. The operation of the apparatus used when an outgoing call is made

over the trunk conductors 1 and 2 will now be described; as previously stated the conductors 138', 139, and 140 terminate in a set of bank contacts in local branch exchange first selectors; upon a subscriber seizing these 70 contacts by operating one of these selectors ground is placed on the conductor 139, a circuit may now be traced from the said ground, break springs 146, break springs 147 lower winding of relay 4 to battery. Relay 75 4 will attract its armature, cutting off at springs 148 and 149 the selector E from the trunk line 1 and 2. Therefore this trunk can be used in the usual manner for an outgoing call to the main exchange.

Referring now to Fig. 4; this is a modification of the system above described and is adapted to operate in a small exchange of not over 100 subscribers. Its operation is very similar to that hereinbefore described and will be readily understood with but a brief description. Upon the trunk line 201 and 202 being seized a circuit is completed for the line relay 203 of connector L which will energize and complete the circuit of slow acting relay 204. Relay 204 operates to prepare the vertical magnet circuit and to place ground on the release trunk conductor 205 to prevent the trunk line 201 and 202 being seized for an outgoing call. When 90 the next digit of the desired number is called the line relay 203 will operate in the usual manner to complete a circuit for the vertical magnet 207 in series with slow acting relay 208. Upon the last digit being 95 called the line relay completes the circuit of the rotary magnet 230 in multiple with relay 210 in the usual manner, to connect with the line of the subscriber shown at B. If the called line is busy, the busy test relay 100 211 will be energized and the busy tone will be transmitted to the calling subscriber. If the line is idle, relay 212 will operate and the subscriber B will be rung. Upon the removal of his receiver the ring cut off relay 105 213 will operate to extend the called subscriber's line to the back bridge relay 214, which will attract its armature and operate the reversing relay 215 to reverse the polarity of the trunk conductors 201 and 202 and 110 place ground on the vertical and rotary test wipers 224 and 231 respectively. This ground will extend from bank contacts 232 and 233 to the vertical and rotary test contacts in the finder switch N interlinked with the connector L. When the conversation is completed both parties will replace their receivers on the switchhook, after which, the release will take place in the well known manner.

So far the operation of the connector L 125 has been practically identical with that of connector H but if the subscriber B should transfer the call, the operation would be slightly different from that hitherto described. Assuming this to be the case, the 130

party B will operate his dial for the digit one, whereupon the back bridge relay will retract armature once and transmit an impulse from ground G^{18} to relay 217. Relay 5 217 attracts its armature and locks to ground G^{19} through off normal springs 219. Relay 217 also places ground G^{20} on conductor 221 at springs 220 thereby completing a circuit to the vertical magnet 222 of the finder 10 switch N. The vertical magnet of finder N operates in the same manner as that of finder G, interrupting its own circuit at springs 234 until the vertical wiper 223 engages the grounded vertical test contact 235, 15 ground being placed on the multiple 232 by the vertical wiper of the connector switch L, whereupon relay 225 will energize, lock itself to ground on conductor 236 at springs 237, and transfer the operating circuit to 20 the rotary magnet 238 at springs 239.

The rotary magnet will continue to rotate the switch until the rotary test wiper 240 engages the grounded test contact 241, whereupon relay 226 will energize, lock 25 itself to ground on conductor 236, and complete the release magnet circuit for the connector L at springs 242. The circuit being traced from ground on conductor 236, springs 242, conductor 243, springs 244, 30 springs 245, release magnet 209 to battery. This will restore the connector switch to normal whereupon relays 214, 215, 217, 213 and 212 will deenergize. Upon relay 217 retracting its armature a circuit is completed 35 from ground G^{21} , conductor 252, springs 251 conductor 253, relay 254 to battery. Relay 254 attracts its armature, locks to ground on conductor 236, and prepares a circuit for the release magnet 228 of finder N.

40 It must be here mentioned that upon the first vertical step of the shaft of finder switch N ground was placed on conductor 236 at off normal springs 246 therefore relay 227 in the connector switch L will energize and serve to open the calling subscriber's loop to the line relay 203 and keep the 45 polarity of the trunk conductors 201 and 202 reversed, battery being supplied from the windings of relay 228.

50 As soon as the finder N connects with the multiples of the B subscriber's line a tone will be connected to the line from tone machine V over the energizing circuit of line relay 203 including the calling device of the 55 subscriber B. By operating his dial the party B may control line relay 203 to cause the connector switch L to connect with another subscriber's line in precisely the same manner as hereinbefore described. Should 60 this line be busy, or not answer, the party B may converse with the calling subscriber, and if another connection is necessary, the party B, may release the connector switch L by replacing his receiver on the switch hook 65 whereupon the connection will release in the

usual manner. Upon the subscriber B removing his receiver he will still be connected with the connector L because, ground G^{21} was placed on the private conductor 249 to hold the line switch in the correct position, 70 by wiper 248. The subscriber B may now call another number and operate the connector to connect with a third party. Prior to the answer of the second called party the calling party could by hanging up his receiver complete a circuit for the release of the finder N and consequently the connector L also. Upon this subscriber answering he will energize the back bridge relay 214, to complete the circuit of reversing relay 215, 75 which on attracting its armature 250 places ground G^{22} , on conductor 254, springs 255, springs 237, release magnet 228 to battery. Upon the finder N restoring to normal, 80 ground would be removed from conductor 236, therefore, all the relays of the finder would restore to normal and relay 227 of the connector would retract its armature and the calling and second called party would be able to converse over the same circuit 90 through the connector as before used. All the apparatus used for the passing is now restored to normal and consequently the second called party may pass the call to a third subscriber and so on indefinitely. 95

The trunk line 201 and 202 may also be used for an outgoing call, being seized over the multiple 205, 206 and 207. Ground will be placed on the release trunk conductor 205, thus completing a circuit for the upper 100 winding of cutoff relay 228, which will energize and cut off the connector L from the trunk. This trunk may now be used to establish an outside connection.

It will, therefore, be seen that I have provided a simple and highly efficient method of extending or transferring calls in a large or small automatic exchange and that this result is attained in a novel and highly improved manner. 105

Having fully described and ascertained the features and operation of my invention what I consider to be new and desire to have protected by Letters Patent will be pointed out in the appended claims. 110

1. In a telephone system, a selector and connector switch, means for operating said switches in succession to connect with a called subscriber's line, and means including a finder switch under the control of the said called subscriber to reoperate said selector switch while maintaining said connector operated. 120

2. In a telephone system, a selector and connector switch, means for operating said switches in succession to connect with a called subscriber's line and means whereby the said called subscriber may release and reoperate said selector while maintaining said connector operated. 125

3. In a telephone system, a selector switch, connector switches accessible thereto, means for operating said selector and one of said connectors to connect with a called line, means controlled over the established connection for reoperating the same elements of said selector switch and another connector switch to pass the call to a second called subscriber.
4. In a telephone system, a selector switch, connector switches accessible thereto, means for operating said selector and a connector to establish a connection to a called subscriber's line, means under the control of the subscriber on the connected called line for reoperating the same elements of said selector switch to extend the connection to a second called subscriber's line, and means whereby said first called party may release said last extended connection.
5. In a telephone system, an automatic selector and connector switch, means for operating said switches in succession to connect with a called subscriber's line, a relay in said connector controlled over the called line and means controlled by said relay when thus controlled over said called line for again operating said selector to transfer the connection to a second called subscriber's line.
6. In a telephone system, a calling subscriber's line, connector switches, a selector switch controlled over said line to select one of said connector switches, means for operating said connector to connect with a called subscriber's line, means under the control of the subscriber on the connected called line for releasing and reoperating said selector switch over a portion of the established connection to extend the call to a second called line.
7. In a telephone system, a trunk line, an automatic switch associated therewith, other automatic switches accessible to said switch, means for seizing said trunk line and for operating said first automatic switch to seize one of said second switches, and for operating the seized second switch to extend a connection to a called line, and connections whereby the same elements of said first automatic switch may be operated again over the connected called line to establish a connection with a second called line.
8. In a telephone system, a trunk line, a pair of automatic switches associated with said trunk line, other automatic switches accessible to said pair of switches, means for seizing said trunk line and for operating one of said pair of switches to seize one of said second switches, and for operating the seized second switch to extend a connection to a called line, and connections whereby the first one of said pair of automatic switches may be operated again from the connected called line through the seized second switch and the other of said pair to establish a connection to a second called line.
9. In a telephone system, a trunk line, a pair of automatic switches associated with said trunk line, other automatic switches accessible to said pair of switches, means for seizing said trunk line and for operating one of said pair of switches to seize one of said second switches, and for operating the seized second switch to extend a connection to a called line, and connections whereby the first one of said pair of automatic switches may be operated again from the connected called line through the seized second switch and the first of said pair to establish a connection to a second called line, and means for releasing the second switch of said pair responsive to the removal of the receiver on said second called line.
10. In a telephone system, selector switches, automatic switches individual thereto, connector switches accessible to said selector switches, means whereby a calling subscriber may operate one of said selectors to extend a connection to a called line through one of said connector switches, and means whereby the subscriber of the called line may operate the associated automatic switch to release said first used selector.
11. In a telephone system, selector switches, automatic switches individual thereto, connector switches accessible to said selector switches, means whereby a calling subscriber may operate one of said selectors to extend a connection to a called line through one of said connector switches, means whereby the subscriber on the called line may operate the associated automatic switch to release said first used selector, and means then operable whereby said calling subscriber may operate said first used selector switch to extend a connection to a second called line through a second one of said connector switches.
12. In a telephone system, automatic selector switches, connector switches accessible thereto, means controlled by a calling subscriber for seizing a selector switch and for then operating it to select one of said connector switches, and for operating said connector switch to find a called line, together with means controlled from the called line over a part of said extended connection for operating the same elements of said first seized selector and another connector to extend a connection to a second called subscriber.
13. In a telephone system, a trunk line for handling incoming calls to a branch exchange, a selector switch in which said trunk line terminates, connector switches accessible to said selector, means for successively operating said selector and connector to connect with a called subscriber's line, means whereby the subscriber on the connected

- called line can release the said selector while maintaining connection with said calling line and means for reoperating said selector to transfer the call to another line.
14. In a telephone system, a selector switch, trunk lines accessible thereto terminating in connector switches, means for operating said selector switch to connect with one of said trunk lines and for then operating the selected connector switch to connect with a called subscriber's line, means for closing a bridge across the selected trunk line, and means responsive to the closure of said bridge for releasing said selector switch.
15. In a telephone system a selector and connector switch, means for operating said switches in succession to establish a talking connection with a called subscriber's line, a finder switch, means controlled over the called line by a called subscriber for causing said finder switch to establish an alternative talking connection to said called subscriber's line and release said selector switch.
16. In a telephone system a plurality of selector switches, connector switches, means for operating successively, a plurality of selector switches and a connector switch to connect with a called subscriber's line, means whereby the subscriber on the said called line may reoperate the same elements of one of said selector switches over a portion of the first extended connection to transfer the call to a second party.
17. In a telephone system, selector and connector switches, means for operating a selector and connector switch to connect with a called subscriber's line, means whereby the said called subscriber may reoperate said selector switch to extend a connection to a second called party, and means whereby the second called party can operate the same elements of said selector again to connect with another party while connection is still maintained with said calling line.
18. In a telephone system, selector and connector switches, means for operating successively a plurality of selectors and a connector switch to connect with a called subscriber's line, means whereby the said called subscriber may reoperate the same elements of the selector switch used and another connector switch to extend the connection to a second called subscriber's line and means responsive to the removal of the second called party's receiver for releasing said first established connection.
19. In a telephone system, a selector switch, a finder switch, connector switches accessible to said selector switch, means for seizing said selector and operating it to select one of said connector switches, and for operating the selected connector switch to find a called line, a relay in said selector switch, a means whereby said relay is controllable over the extended connection by the subscriber on the called line for initiating the operation of said finder switch.
20. In a telephone system, a selector switch, a finder switch, trunk lines accessible to said selector and finder terminating in connector switches, means for seizing said selector switch and operating it to select one of said trunk lines, and for operating the seized connector switch to extend a connection to a called line, a relay in said selector switch, and means whereby said relay is controllable over the extended connection by the subscriber on the called line to initiate the operation of said finder switch to find said selected trunk line.
21. In a telephone system, a selector switch, a finder switch, trunk lines accessible to said selector and finder terminating in connector switches, means for seizing said selector switch and operating it to select one of said trunk lines, and for operating the seized connector switch to extend a connection to a called line, a relay in said selector switch, means whereby said relay is controllable over the extended connection by the subscriber on the called line to initiate the operation of said finder switch to find said selected trunk line.
22. In a telephone system, a selector switch, a finder switch, trunk lines accessible to said selector and finder terminating in connector switches, means for seizing said selector switch and operating it to select one of said trunk lines, and for operating the seized connector switch to extend a connection to a called line, a relay in said selector switch, means whereby said relay is controllable over the extended connection by the subscriber on the called line to initiate the operation of said finder switch to find said selected trunk line, means operated upon said finder finding said trunk line to release said selector.
23. In a telephone system, a selector switch, a finder switch, trunk lines accessible to said selector and finder terminating in connector switches, means for seizing said selector switch and operating it to select one of said trunk lines, and for operating the seized connector switch to extend a connection to a called line, a relay in said selector switch, means whereby said relay is controllable over the extended connection by the subscriber on the called line to initiate the operation of said finder switch to find said selected trunk line, and means operated upon said finder finding said trunk line to release said selector and means then operable whereby the said called subscriber may again operate said selector to seize a connector switch and for operating said connector switch to connect with a second called subscriber's line.

tive responsive to the second called subscriber removing the receiver from the switchhook for releasing said finder switch.

24. In a telephone system, subscribers' lines, means for establishing a talking connection from a calling to a called one of said lines, and means common to a plurality of subscribers' lines controlled by the called subscriber over the established connection for opening said talking circuit at one point and for establishing a new talking circuit around said opening.

25. In a telephone system, subscribers' lines, means for establishing a talking connection from a calling to a called one of said lines, means common to a plurality of subscribers' lines controlled by the called subscriber over the established connection for opening said talking circuit at one point and for establishing a new talking circuit around said opening, and means controlled over said new talking circuit for extending said talking circuit to include a second called subscriber's line.

26. In a telephone system, a trunk line, means for extending a connection from said trunk line to a called subscriber's line through a plurality of successively operated switches, and means controlled from the called line for extending the connection to a second called party by releasing and reoperating one of said switches used in said first established connection, while a connection is still maintained between the calling and first called line and means for thereafter releasing said connection.

27. In a telephone system, a switch for connecting calling and called subscribers' lines, a back bridge and a front bridge for said switch, said back bridge including a relay, a finder switch, means under the control of said relay for cutting off said front bridge, and means responsive to the disconnection of said front bridge for initiating the operation of said finder switch.

28. In a telephone system, a calling subscriber's line, a series of automatic switches for connecting said line with a connector switch over a trunk line, and means for operating said connector switch to connect with a called subscriber's line, a front bridge across the conductors of said trunk line, and means under the control of the called subscriber for disconnecting said front bridge from said trunk line and maintaining said front bridge energized.

29. In a telephone system, a calling subscriber's line, a connector switch, a series of automatic switches for connecting said line with said connector switch over a trunk line, and means for operating said connector switch to connect with a called subscriber's line, a front bridge across the conductors of said trunk line, means under the control of

the called subscriber for disconnecting said front bridge, and for establishing a short circuit across said trunk conductors, and means under the control of the called subscriber for opening and closing said short circuit.

30. In a telephone system, a calling subscriber's line, a connector switch, a series of automatic switches for connecting said line with said connector switch over a trunk line, and means for operating said connector switch to connect with a called subscriber's line, a front bridge across the conductors of said trunk line, means under the control of the called subscriber for disconnecting said front bridge, and for establishing a short circuit across said trunk conductors, and means under the control of the called subscriber for opening and closing said short circuit to send impulses back over said trunk line, to reoperate one of said series of automatic switches to transfer the call to a second called subscriber.

31. In a telephone system, a calling subscriber's line, a series of automatic switches for connecting said line with a connector switch over a trunk line and means for operating said connector switch to connect with a called subscriber's line, a front bridge across the conductors of said trunk line, means under the control of the called subscriber for disconnecting said front bridge from said trunk line, and means responsive to the cutting off of said front bridge for releasing one of said series of switches.

32. In a telephone system, main and auxiliary switches permanently connected in pairs, means whereby a calling subscriber can operate one of said main switches to connect with a called line and means whereby the subscriber on the called line can reoperate said main switch through said auxiliary switch to transfer the call to a second called line.

33. In a telephone system, main and auxiliary switches permanently connected in pairs, means whereby a calling subscriber can operate one of said main switches to connect with a called line, means whereby the subscriber on the called line can reoperate said main switch through said auxiliary switch to transfer the call to a second called line, and automatic means for releasing said auxiliary switch responsive to the response of the second subscriber.

34. In a telephone system, a calling subscriber's line, a connector switch, a series of automatic switches for connecting said line with said connector switch over a trunk line, means for operating said connector switch to connect with a called subscriber's line, a front bridge across the conductors of said trunk line, means under the control of the called subscriber for disconnecting said

- front bridge from said trunk line, and means responsive to the cutting off of said front bridge for releasing one of said series of switches and for placing said released switch under the control of said called subscriber. 65
35. In a telephone system, a trunk line, a pair of permanently connected automatic switches, means for operating one of said switches over said trunk line to connect with a called telephone line, and connections between said switches whereby the said switch may be reoperated through said other switch over the connected called line to establish a connection with another called line. 70
36. In a telephone system, automatic switches permanently connected in pairs, subscribers' lines accessible thereto, means whereby a calling subscriber may operate one of said switches to connect with a called subscriber's line, and means whereby the subscriber on the called line can initiate the operation of the other of said pair of switches to find his line. 75
37. In a telephone system, automatic switches permanently connected in pairs, subscribers' lines accessible thereto, means whereby a calling subscriber may operate one of said switches to connect with a called subscriber's line, means whereby the subscriber on the called line can initiate the operation of the other of said pair of switches to find his line, and means responsive to said switch finding said line for releasing said first switch placing it under the control of the said called subscriber. 80
38. In a telephone system, automatic switches permanently connected in pairs, subscribers' lines accessible thereto, means whereby a calling subscriber may operate one of said switches to connect with a called subscriber's line, means whereby the subscriber on the called line can initiate the operation of the other of said pair of switches to find his line, means responsive to said switch finding said line for releasing said first switch and placing it under the control of the said called subscriber, and means whereby the said called subscriber may operate the first switch to establish a connection with another called line. 85
39. In a telephone system, automatic switches permanently connected in pairs, subscribers' lines accessible thereto, means whereby a calling subscriber may operate one of said switches to connect with a called subscriber's line, means whereby the subscriber on the called line can initiate the operation of the other of said pair of switches to find his line, means responsive to said switch finding said line for releasing said first switch and placing it under the control of the said called subscriber, means whereby the said called subscriber may operate the first switch to establish a connection with another called line, and automatic means for releasing said other switch upon the response of the second called subscriber. 90
40. In a telephone system, automatic switches permanently connected in pairs, subscribers' lines accessible thereto, means whereby a calling subscriber may operate one of said switches to connect with a called subscriber's line, means whereby the subscriber on the called line can initiate the operation of the other of said pair of switches to find his line, means responsive to said switch finding said line for releasing said first switch and placing it under the control of the said called subscriber, means whereby the said called subscriber may operate the first switch to establish a connection with another called line, and means whereby said first called party can release said last connection and call a third subscriber. 95
41. In a telephone system, a selector switch, connector switches accessible thereto, means for operating said selector and a connector to establish a connection to a called subscriber's line, means under the control of the subscriber on the connected line for reoperating the same elements of said selector switch to extend the connection to a second called subscriber's line, and means whereby said first called party may release said last extended connection. 100
42. In a telephone system, selector switches, connector switches, means for operating a plurality of said selector switches and a connector switch to connect with a called subscriber's line, a finder switch, and means under the control of the subscriber on the connected called line for operating said finder switch to establish a new talking connection independent of the wipers of said selector switch. 105
43. In a telephone system, a selector and connector switch, means for controlling said switches in succession to connect with a called subscriber's line, a finder switch, and means operated at will by a subscriber at the station on the called line for causing said finder switch to establish an alternative talking connection around said selector switch. 110
44. In a telephone system, telephone lines, automatic switches controlled from a calling one of said lines for extending a connection to a called one of said lines, means for supplying battery to said calling line, relay controlled means operative upon the response of the subscriber on the called line for reversing the direction of said battery supply, means controlled from said called line for then extending said connection to another called one of said lines, and retaining means for maintaining the direction of 115
- 120
- 125

current flow reversed after the receiver is replaced at the first called station and before a response is obtained at the second called station.

5 45. In a telephone system, telephone lines, automatic switches, means under the control of a party on a calling one of said lines for operating a series of said switches in order to extend a connection to a first called one of said lines, means under control of the party on the said called line for reversing the direction of current projected back over the calling line, means controlled from the party on the said called line for directly extending a connection to a second called line from a point intermediate of the calling and the called lines, means for the party on the first called line disconnecting while maintaining the connection from the calling line to the second called line and for maintaining the said reversed direction of current regardless of the responded or non-responded condition of the second called line, and means for reversing the current direction projected back over the calling line to the initial direction consequent to the party on the second called line responding and subsequently disconnecting.

46. In a telephone system, telephone lines, automatic switches, means under the control of a party on a calling one of said lines for operating a series of said switches in order to extend a connection to a first called one of said lines, means under control of the party on the said called line for directly extending a connection to a second called line from a point intermediate of the calling and the called lines, and means for the party on the first called line disconnecting while maintaining the connection from the calling line to the second called line and for maintaining the said changed character of current regardless of the responded or non-responded condition of the second called line.

47. In a telephone system, telephone lines, automatic switches, means under the control of a party on a calling one of said lines for operating a series of said switches in order to extend a connection to a first called one of said lines, means under control of the party on the said called line for changing the character of current projected back over the calling line, means controlled from the party on the first called line disconnecting while maintaining the connection from the calling line to the second called line and for maintaining the said changed character of current regardless of the responded or non-responded condition of the second called line.

current regardless of the responded or non-responded condition of the second called line, and means for restoring the character of current projected back over the calling line to the initial character consequent to the party on the second called line responding and subsequently disconnecting.

48. In a telephone system, lines, automatic switch mechanism, means under control of a party on a calling one of said lines for operating said switch mechanism in order to extend a connection to a first called one of said lines, means controlled from the said called line for reversing the direction of current projected back over the calling line, means controlled by the party on the said called line for directly extending a connection to a second called line from a point intermediate of the calling and the called line, and means for the party on the first called line disconnecting while maintaining the connection from the calling line to the second called line for maintaining the said reversed direction of current regardless of the responded or non-responded condition of the second called line.

49. In a telephone system, lines, automatic switch mechanism, means under control of a party on a calling one of said lines for operating said switch mechanism in order to extend a connection to a first called one of said lines, means controlled from the said called line for reversing the direction of current projected back over the calling line, means controlled by the party on the said called line for directly extending a connection to a second called line from a point intermediate of the calling line and the called line, means for the party on the first called line disconnecting while maintaining the connection from the calling line to the second called line and for maintaining the said reversed direction of current regardless of the responded or non-responded condition of the second called line, and means controlled over the second called line for restoring the direction of current.

50. In a telephone system, lines, automatic switch mechanism, means under control of a party on a calling one of said lines for operating said switch mechanism in order to extend a connection to a first called one of said lines, means controlled from the said called line for reversing the direction of current projected back over the calling line, means controlled by the party on the said called line for directly extending a connection to a second called line from a point intermediate of the calling line and the called line, means for the party on the first called line disconnecting while maintaining the connection from the calling line to the second called line and for maintaining the said reversed direction of current regardless of the responded or non-responded condition of the second called line.

condition of the second called line, and automatic means effective in a predetermined time to restore the direction of current.

51. In a telephone system, a called trunk line, a calling subscriber's line, a first connecting means operated over the calling line for connecting the calling line with the trunk line, a second connecting means for connecting the trunk line with the calling line, other means controlled over the trunk line responsive to a manual operation ensuing after said connection has been established for effectively operating the second means and for breaking down the connection established by the first means, and means controlled over the calling line for destroying the connection.

52. In a telephone system, a called two conductor trunk line, a calling subscriber's line, a first connecting means operated over the calling line for connecting the calling line with the trunk line, a second connecting means for connecting the trunk line with the calling line, other means controlled over a conductor of the trunk line for effectively operating the second means and for breaking down the connection established by the first means, and means controlled over the trunk line for destroying the connection.

53. In a telephone system, a called trunk line, a calling subscriber's line, a first connecting means operated over the calling line for connecting the calling line with the trunk line, a second connecting means for connecting the trunk line with the calling line, other means controlled over a talking conductor of the trunk line for effectively

operating the second means and for breaking down the connection established by the first means, and means controlled over the trunk line or alternatively over the calling line for destroying the connection.

54. In a telephone system, a trunk line, a calling line, a called line, a first connecting means for connecting the calling line with the trunk line, a second connecting means for connecting the trunk line with the calling line, a third connecting means for connecting the trunk line with the called line to complete a connection from the calling line to the called line, and other means controlled over a talking conductor of the called line for effectively operating the second means and for breaking down the connection established by the first means.

55. In a telephone system, a trunk line, a calling line, a called line, a first connecting means for connecting the calling line with the trunk line, a second connecting means for connecting the trunk line with the calling line, a third connecting means for connecting the trunk line with the called line directly controlled from the calling line in order to complete a connection from the calling line to the called line, and other means automatically controlled from the called line consequent to a manual response thereon for effectively operating the second means and for breaking down the connection established by the first means.

Signed by me at Chicago, Cook County, Illinois, this 18th day of September, 1920.

JOHN E. GARDNER.
